UNITED STATES PATENT OFFICE.

ALBERT C. BAUGHMAN, OF GRISWOLD, IOWA.

CORN-HUSKING IMPLEMENT.

No. 886,033.

Specification of Letters Patent. Patented April 28, 1908.

Application filed September 24, 1907. Serial No. 394,424.

To all whom it may concern:

Be it known that I, ALBERT C. BAUGHMAN, a citizen of the United States, residing at Griswold, Cass county, State of Iowa, have 5 invented a new and useful Corn-Husking Implement; and I do hereby declare that the following is a full, clear, and exact description thereof, which will enable others skilled in the art to which it appertains to 10 make and use the same, reference being had to the drawings, and to the letters of reference marked thereon, which form a part of this specification.

My invention pertains to corn husking 15 implements; and it consists in the implement, hereinafter described and claimed, specifically constructed with a view of being expeditiously and easily applied to the hand subsequent to the placing of a mitten there- 20 on, and of being used to advantage over the mitten.

In the drawings accompanying and forming part of this specification: Figure 1 is a 25 perspective view, nearly a plan view of my novel corn husking implement. Fig. 2 is a side view of the same. Fig. 3 is a plan view showing my novel implement as properly arranged relative to a mitten and also showing by dotted lines the arrangement of the 30 hand of the implement user in the mitten and in proper position relative to the implement.

Similar letters designate corresponding 35 parts in all of the views of the drawings, referring to which:

D is a mitten which may be and preferably is of the conventional construction.

My novel corn husking implement is 40 formed of a single piece of steel or other material suitable to the purpose; and it comprises a blade C of about the proportional length illustrated, a loop A at the heel of the blade, preferably of sufficient size to receive the third and fourth fingers of an operator's 45 hand, and a tongue B depending from the end of the loop A remote from the heel of the blade C and separated from the blade by an intervening space designed to serve an important purpose which will now be set forth.

50 In using my improvements, the corn husker first places the mitten D upon his hand, and then applies the implement. In thus applying the implement, the husker compresses the material of the mitten D at 55 a point between the third and fourth fingers

of the operator's hand, and then slips the implement on the end of the mitten and up toward the wrist of the operator until the tongue B assumes the position shown in Fig. 3 between the third and fourth fingers of the 60 operator's hand. When the implement is thus positioned relative to the mitten and the hand, it will be manifest that the blade C extends across the palm of the mitten, and a portion of the mitten and the third and 65 fourth fingers of the operator's hand are confined within the loop A of the implement, with the result that the operator is enabled to use the implement to the best advantage. It will also be apparent from the foregoing 70 that the implement may be readily removed from the hand with the mitten and may almost if not quite as readily be removed from both hand and mitten while the latter remains on the hand. 75

Notwithstanding the adaptability of my novel corn husking implement to be readily applied and worn over a mitten and as readily removed from the mitten, it will be gathered from the foregoing that the implement 80 is quite as simple and inexpensive as the ordinary implements of corresponding type at present in use.

I am well aware that a corn husker comprising a body or major portion, and a clasp 85 at one end of said body or major portion, adapted to receive a forefinger and having its end separated from said body or major portion by an intervening space, is old. I therefore make no claim to anything in common 90 with said husker.

What I claim is:

As a new article of manufacture, the herein described corn-husking implement formed of a single piece of material of even thickness 95 throughout, and consisting essentially of a blade, a loop at the heel of the blade, of a length to receive the third and fourth fingers of an operator's hand, and a depending tongue at the end of the loop remote from the heel 100 of the blade; the end of the said tongue being separated from the blade by an intervening space, and the said space being arranged and being of a size to receive the thicknesses of the palm portion and back portion of a 105 mitten.

ALBERT C. BAUGHMAN.
